The ornamental design for an attachable handle for holder for hygienic wipes, as shown and described.

DESCRIPTION

FIG. 1 is a front right side perspective view of my new, original, and ornamental design of an attachable handle for holder for hygienic wipes;

FIG. 2 is a right side view thereof;

FIG. 3 is a bottom plan view thereof;

FIG. 4 is a left side view thereof;

FIG. 5 is a top plan view thereof;

FIG. 6 is a rear view thereof;

FIG. 7 is a front view thereof; and,

FIG. 8 is a front left side perspective view thereof.

The broken lines in the drawings illustrate portions of the attachable handle for holder for hygienic wipes that form no portion of the claimed design.

The claimed design relates to an attachable handle for a personal hygiene tool which may be used to hold a hygienic wipe, e.g., toilet paper, which a person may use for extended reach in wiping the person's bottom.
